UNITED STATES PATENT OFFICE.

JOHN EDWARD GOODWIN, OF STOKE-UPON-TRENT, ENGLAND, ASSIGNOR TO JOSIAH WEDGWOOD & SONS, INCORPORATED OF AMERICA, OF NEW YORK, N. Y., A CORPORATION OF NEW YORK.

DESIGN FOR A PLATE OR SIMILAR ARTICLE.

61,300.

Specification for Design.

Patented Aug. 1, 1922.

Application filed October 29, 1921. Serial No. 511,541. Term of patent 14 years.

To all whom it may concern:

Be it known that I, JOHN EDWARD GOODWIN, a subject of Great Britain, residing at 13 Wilson Street, Stoke-upon-Trent, Staffordshire, England, have invented a new, original, and ornamental Design for a Plate or Similar Article, of which the following is a specification, reference being had to the accompanying drawing, forming part thereof.

Fig. 1 is a plan view of a plate showing my new design applied thereto, it being understood that the marginal design is repeated around the entire circumference of the article; and

Fig. 2 is a side elevation thereof, partially in section.

While the design is here shown applied to a plate, it is applied, with suitable adaptations, to the various dishes of a complete set, and my invention is not limited to its application to a plate.

I claim:

The ornamental design for a plate or similar article as shown and described.

In testimony whereof I have signed my name to this specification.

JOHN EDWARD GOODWIN.
